UNITED STATES PATENT OFFICE

104,251

DESIGN FOR A SHOE TREE

Julius Gershune, Louisville, Ky.

Application June 17, 1935, Serial No. 57,308

Term of patent 14 years

To all whom it may concern:

Be it known that I, Julius Gershune, a citizen of the United States, residing at Louisville, in the county of Jefferson and State of Kentucky, have invented a new, original, and ornamental Design for Shoe Trees, of which the following is a specification, reference being had to the accompanying drawing, forming part thereof.

Figure 1 is a plan view of a shoe tree, showing my new design.

Figure 2 is a side elevational view of a shoe tree, showing my new design.

Figure 3 is a vertical section on the line 3—3 of Figure 2, showing the appearance of the toe form of the shoe tree, looking at its back end.

A dominant feature of the design resides in the openings on the toe portion which are shaped and arranged to produce an ornamental effect. A further feature resides in the shoulder appearance at the back of the toe portion produced by both sides adjoining the lug which connects to the rear members. A still further feature resides in the heel portion which is shaped into an oblong loop, the back, top and bottom being curved in, and the sides adjacent to the twisted part being flat in surface.

I claim:

The ornamental design for a shoe tree, as shown and described.

JULIUS GERSHUNE.
